AXIAL-FLOW COMPRESSORS

Joseph Szydłowski, Usines Turbomeca, Bordes, France
Filed July 19, 1960, Ser. No. 43,750Claims priority, application France Feb. 3, 1960
8 Claims. (Cl. 230—134)

The present invention relates to improvements in the wheels of axial-flow compressors, and more particularly of such compressors which operate at ultrasonic and supersonic speeds and comprise a wheel or wheels equipped with blades the camber-line of which is curved in opposite directions at the tip and at the root thereof, such as described in the applicant's U.S. Patent No. 2,915,238. Such axial-flow compressors operate with acceptable efficiencies when the Mach number of their flow speed at the tip of the blades is high.

The present invention has for main object to provide means for increasing such efficiencies for equal Mach numbers with respect to those of said axial-flow compressors while permitting the obtention of acceptable efficiencies for higher Mach numbers.

For this purpose, according to the invention, at least one cross-section of the blade and more particularly the cross-section at the tip of the blade has a profile with two successive opposed curvatures while the cross-section at the root has a profile with a single curvature. It is thus possible to obtain an increasing in efficiency ranging from 3% to 4% with respect to the compressors described in the aforementioned U.S. patent.

A further object of the invention is to provide jet engines, gas turbine engines and other similar machines, more particularly aviation machines, with compressors having rotor wheels of the type specified above.

Conveniently, an axial-flow wheel such as specified above is used as the single wheel of a compressor or as the first stage wheel of a multi-stage compressor, or as the single or first stage wheel of the low-pressure compressor of a jet engine, a double-flow jet engine or other similar machines having more than one compressor.

The invention will be better understood and other features thereof will appear by means of the following description of a practical embodiment of the invention, reference being made to the accompanying drawings, in which:

FIG. 1 is a perspective view of an axial-flow compressor wheel constructed according to the invention.

FIG. 2 is a radial view of a blade.

FIG. 3 is a partial developed view of a cylindrical section of the wheel adjacent the blade roots along the line III—III shown in FIG. 1.

FIG. 4 is a partial developed view of a cylindrical section of the wheel adjacent the blade tips along the line IV—IV shown in FIG. 1.

FIG. 5 is a view similar to that of FIG. 2 for a modification of the blade shown in said FIG. 2.

Referring to FIG. 1, a compressor wheel 2 is provided with a plurality of blades 1. The centers c3 and c4 of the cross-section 3 and 4 of each blade (FIGS. 3 and 4) through planes parallel to the plane tangent to the rotor at the blade root and passing through the lines III—III and IV—IV of FIG. 1 are substantially aligned from the blade root to the blade tip along the radius passing through the center c3 of the blade foot.

Each blade 1 has a trailing edge 6 and a leading edge 5 which curve in opposite directions, the trailing edge 6 having a spanwise curvature from the radial inner end of the blade to its radial outer end in a counter rotating direction with respect to the direction of rotation F of the wheel while the leading edge 5 has a spanwise curvature in said direction of rotation. Such curvatures are so determined that the blade is flared at its tip.

2

As illustrated in FIGS. 3 and 4, the chordal pitches p3 and p4 of the cross-sections 3 and 4 numerically decreases from a positive value p3 from the root to a positive value p4 at the tip of the blade, whereby the chord 5 7—8 of the cross-section 3 at the blade root is slightly inclined to the axis of rotation A of the wheel 2 in the direction F of the wheel rotation. The chords of the successive cross-section from the blade root to the blade tip are more and more inclined to said axis so that the chord 9—10 of the cross-section 4 at the blade tip forms a substantially greater angle with said axis A than does the cross-section at the root.

At the blade root the cross-section has a single curvature and a concave-convex shape, the concave curve C3 being on the pressure side of the blade and the convex curve on the back side thereof. Near the blade tip the cross-section has a configuration with two successive opposed curvatures. The curve C4 on the pressure side of the blade comprises, close to the leading edge 5, a convex curve portion C4a and close to the trailing edge 6 a concave curve portion C4b. The curve on the back side of the blade near the blade tip has a concave portion close to the leading edge and a convex portion close to the trailing edge. The center of curvature O3 of the concave curve C3 is located with respect to the blade sections in the direction F of the wheel rotation as well as the center of curvature O4b of the concave curve portion C4b close to the trailing edge of the blade. On the contrary the center of curvature O4a of the convex curve portion C4a close to the leading edge of the blade is directed in the direction opposite to said direction F. The intermediate cross-sections of the blade change progressively from the single curvature cross-section C3 to the twin-curvature cross-section C4. The tip of the blade 35 is located in a plane substantially parallel to the plane tangent to the body at the blade root and has an outline similar to that of said twin-curvature cross-section C4.

The wheel of an axial-flow compressor provided with blades of the character described has an increasing in efficiency ranging from 3% to 4%, with respect to that of a compressor according to the aforesaid U.S. patent, other things being the same.

Conveniently, the compressor wheel of the invention is more particularly used with advantage in double flow jet engines and in jet engines of the type described in the following U.S. patents in the name of applicant, No. 2,397,060, No. 2,795,372 and No. 2,922,278, in the U.S. patent application in the name of applicant Ser. No. 653,148 filed April 16, 1957, now abandoned and corresponding to the French Patent No. 1,012,233 patented April 9, 1952 or in the following French patents in the name of applicant: No. 907,666 patented July 9, 1945, No. 908,121 patented August 13, 1945, No. 915,552 patented July 22, 1946, No. 1,046,175 patented July 8, 1953 and No. 1,107,179 patented August 3, 1955.

Of course modifications may be made to the described embodiment without departing from the scope of the invention as defined in the appended claims. Thus, for example and as illustrated in FIG. 5, the curve portions 50 C4c and C4d forming the curve C4 with a twin-curvature instead of being joined together tangentially may be united by a rectilinear portion 11 which is tangent to both curve portions C4c and C4d.

What I claim is:

1. A wheel for an axial flow compressor adapted for operating at ultrasonic and supersonic speeds, said wheel comprising: a body adapted for rotation about an axis, and a plurality of blades supported on said body, said blades having a root at the location where said blades contact said body and a remote tip, said blades also having leading and trailing edges, each blade in cross-sections in planes parallel to a plane tangent to the body

at the blade root having centers which are substantially aligned from the blade root to the blade tip along a radial line, said blades each having a chordal pitch which uniformly decreases from a relatively large positive value at the root of the blade to a relatively small positive value at the tip of the blade, said cross-sections of each blade progressively varying in outline as viewed from a pressure side of the blade from a concave curve at the root of the blade to a curve having successive convex and concave portions at the blade tip, said convex and concave portions being respectively disposed adjacent the leading and trailing edges.

2. A wheel as claimed in claim 1 wherein the trailing edge of each blade has a spanwise curvature from the radial inner end to the radial outer end of the blade in a counter rotating direction with respect to the rotary direction of the wheel while the leading edge of the blade has a spanwise curvature in said rotary direction, said curvatures being sufficient to cause the blade to be flared at the tip thereof.

3. A wheel as claimed in claim 1 wherein the cross-sections of each blade at the root is concave on the pressure side of the blade and convex on the other side of the blade and said cross-sections vary to a shape at the tip respectively having on pressure and back sides convex-concave and concave-convex outlines.

4. A wheel for an axial-flow compressor adapted for operating at ultrasonic and supersonic speeds, said wheel comprising: a body, said body being adapted for rotation about an axis, and a plurality of blades supported at the roots thereof to said body and having a remote tip, said blades further having leading and trailing edges, the trailing edge of each blade having a spanwise curvature from the root to the tip in a counter-rotating direction relative to the rotary direction of the wheel, while the leading edge has a spanwise curvature in said rotary direction, said curvatures being sufficient to cause the blades to be flared at the tips thereof, the centers of the cross-sections of each blade in planes parallel to a plane tangent to the rotor at the blade root being substantially aligned from the blade root to the blade tip along a radial line passing through the center of the blade root, said blades having a chordal pitch numerically decreasing from a relatively large positive value at the root to a relatively small positive value at the tip of the blade while the outline of said cross-sections progressively vary on the pressure side from a concave curve at the blade root to a curve having successive convex and concave portions at the blade tip, said convex and concave portions being respectively disposed close to the leading and trailing edges.

5. An axial compressor having at least one stage with at least one wheel and intended for operation at ultrasonic and supersonic speeds, at least one of the wheels of at least one stage of the compressor including blades supported at the roots thereof on said one wheel, said blades having leading and trailing edges, the centers of the cross-sections of each blade in planes parallel to a plane tangent to the wheel at the blade root being substantially aligned from the blade root to the blade tip along a radial line passing through the center of the blade root, said blades each having a chordal pitch of said cross-sections which numerically decrease from a relatively large positive value at the root to a relatively small positive value at the tip of the blade while the outline of said cross-sections progressively vary as viewed on the pressure side of the blade from a concave curve at the blade root to a curve having successive convex and concave portions at the blade tip, said convex and concave portions being respectively disposed close to the leading and trailing edges.

6. A compressor comprising at least one stage operating at ultrasonic and supersonic speeds, said compressor constituting the inlet compressor of a jet engine, said compressor having at least one wheel in at least one stage of said compressor, said wheel having a plurality of blades including roots and tips and leading and trailing edges, the centers of the cross-sections of each blade through planes parallel to the plane tangent to the wheel at the blade root being substantially aligned from the blade root to the blade tip along a radial line passing through the center of the blade root, said blades having a chordal pitch at said cross-sections which numerically decreases from a relatively large positive value at the root to a relatively small positive value at the tip of the blade while the outline of said cross-sections progressively vary as viewed from the pressure side of the blade from a concave curve at the blade root to a curve having successive convex and concave portions of the blade tip, said convex and concave portions being respectively disposed close to the leading and trailing edges.

7. A compressor comprising at least one stage with at least one wheel operating at ultrasonic and supersonic speeds and acting as low pressure compressor for a double flow jet engine, at least one of said wheels or at least one stage of said compressor having blades including roots and tips and leading and trailing edges, the centers of the cross-sections of each blade through planes parallel to the plane tangent to the wheel at the blade root being substantially aligned from the blade root to the blade tip along a radial line passing through the center of the blade root, said blade having a chordal pitch at said cross-sections which numerically decreases from a relatively large positive value at the root to a relatively small positive value at the tip of the blade while the outline of said cross-sections progressively vary as viewed from the pressure side of the blade from a concave curve at the blade root to a curve having successive convex and concave portions at the blade tip, said convex and concave portions being respectively disposed close to the leading and trailing edges.

8. A compressor having at least one stage operating at ultrasonic and supersonic speeds and forming the inlet compressor of a gas turbine, said compressor comprising at least one wheel forming at least one stage of said compressor and having blades including roots and tips and leading and trailing edges, the centers of the cross-sections of each blade through planes parallel to the plane tangent to the wheel at the blade root being substantially aligned from the blade root to the blade tip along a radial line passing through the center of the blade root, said blades having a chordal pitch at said cross-sections which numerically decreases from a relatively large positive value at the root to a relatively small positive value at the tip of the blade while the outline of said cross-sections progressively vary as viewed from the pressure side of the blade from a concave curve at the blade root to a curve having successive convex and concave portions at the blade tip, said convex and concave portions being respectively disposed close to the leading and trailing edges.
